UNITED STATES PATENT OFFICE

FRANK S. RECE, OF DALLAS, TEXAS

KNOCKDOWN CRIB

Application filed April 30, 1926. Serial No. 105,688.

This invention relates to new and useful improvements in knock-down cribs.

The object of the invention is to provide a crib formed of a small number of elements 5 arranged to be assembled and fastened together in a new and novel, as well as simple and efficient manner.

A further object of the invention is to provide bolts instead of screws for fastening 10 the end and side sections, whereby four bolts rigidly connect the two end sections to one of the side sections.

Another object of the invention is to provide a pair of bottom bars connecting the end 15 sections together with simple fastening devices for securing one of the bars to the end sections, whereby the crib is sufficiently braced to permit one of the side sections to be movable.

20 A still further object of the invention is to provide a crib in which the end sections may be made in duplicate and also in which the side sections may be duplicates and the entire crib secured together with a small number 25 of bolts, by the removal of which the crib elements may be knocked down and packed in a flat package.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is an elevation of a crib constructed in accordance with my invention, the movable side section being slid under the bottom bars.

40 Fig. 2 is a plan view of the same.

Fig. 3 is a transverse vertical sectional view taken on the line 3—3 of Fig. 2.

Fig. 4 is a detail of one of the seats or sockets for the end of the bottom bar,

45 Fig. 5 is an enlarged sectional view taken on the line 5—5 of Fig. 2,

Fig. 6 is a horizontal sectional view taken on the line 6—6 of Fig. 1, and

50 Fig. 7 is a detail of one of the fastening members.

In the drawings, the numeral 10 designates one of the end sections or members of a crib and 11 the other end section or member. Each section is a duplicate of the other and comprises upright corner posts 12 having 55 casters 13 at their lower ends and connected at a suitable elevation by an ornamental panel 14. Each panel 14 has a bottom cross bar 15.

I provide a pair of duplicate side sections or members 16 and 17 respectively, and each 60 comprises a rectangular frame 18 and an ornamental panel 19. The section 16 is placed between the end sections, flush with the sides thereof and abutting the inner faces of the corner posts 12 at one side of the crib. The 65 said posts are cut back to receive the side section 16 and provided with shoulders 20 on which said section rests. Bolts 21 are passed through the corner posts and the ends of the frame 18 near the top and bottom of said 70 section. Wing nuts 22 (Fig. 6) are mounted on the inner ends of said bolts within the panel 19. It will be seen that four bolts thus fasten the end sections to the side section 16 and only the heads of the bolts are exposed 75 at the ends of the cribs. This makes a simple and quick manner of fastening or disassembling.

On the inner faces of the bottom cross bars 15 of the end sections are secured guide rails 80 or runners 23 on which the other side section 17 may rest and slide when it is lowered. Spaced above the runners sills 24 are fastened to the inner faces of the bars 15 and each sill 85 has notches or seats 25 cut in its upper portions a short distance from each side of the crib. Bottom tie bars 26 have lugs 27 at each end engaging in said seats. One of the bars 26 has at each end, a hinged fastener comprising leaves 28 and 29, respectively.

The leaf 28 of each fastener is secured by screws to the sills 24, so that when the lugs 27 are in the seats 25, the leaves 29 may be 90 swung against the inner side of the bar 26. Each leaf 29 has an aperture 30 registering with an aperture 31 in the said bar 26. A bolt 32 is passed through the apertures, at each end of the said bar and receives a wing nut 33. It is pointed out that six bolts fasten 95 100

the entire crib together and the two bars 26, constitute its bottom.

The use of the bolts 21 for securing the end and side sections is of great advantage, where the crib is built of such woods as maple and walnut, because holes may be bored for said bolts, but if screws were used the wood would either be split or difficulty would be experienced in inserting them. It will be seen that by removing six bolts the crib may be quickly knocked down. As the slideable section 17 is covered by my co-pending application, Ser. No. 704,816, and may be operated in various ways, I shall not attempt to describe the same in detail. The section 17 is suitably arranged to hinge when pulled out so that it may be folded up against stops 34 on the inner faces of the corner posts 12 and suitably fastened in an upright position.

An advantage of the invention is that the end sections 10 and 11 may be made in duplicate or individual designs as is desired. This is also true of the side sections. Such an arrangement makes for economical manufac-

ture.

Various changes in the size and shape of the different parts, as well as modifications and alterations, may be made within the scope of the appended claims.

What I claim, is:

1. In a knock-down crib, a pair of end sections, a side section removably secured thereto, sills on the bottoms of the end sections having seats, bottom bars having lugs at their ends engaging in said seats, hinged members secured to said sills, fastening bolts passed through the front bottom bar and said hinged members, nuts mounted on said bolts, and a movable side section disposed between said end sections.

2. In a knockdown crib, a pair of end sections, a side section rigidly connecting the end sections and removably attached thereto to form three connected sections with an open front, a sill upon the lower portion of the inner side of the end sections and having seats, an independent front bar having its ends engaging in said seats and abutting the sills and end sections, and fastening devices detachably connecting the inner face of the sills and the front bottom bar.

3. In a knockdown crib, a pair of end sections, side sections rigidly connecting the end sections and removably attached thereto, a sill upon the lower portion of the inner side of the end sections and having seats, independent bottom bars having their ends engaging in said seats and abutting the sills and end sections, an angular fastening device detachably connecting the sills and the front bottom bar, and a slide beneath the sills to receive one of said side sections.

4. In a knockdown crib, a pair of end sections having shoulders at their lower inner

faces, a side section supported by said shoulders, bolts extending through the end sections and the ends of the side section and provided with removable nuts, sills on the bottom of the end sections having seats, independent bottom bars abutting at their ends the sills and end sections and having lugs disposed in said seats, and angle fasteners secured to the inner faces of the sills and the front bottom bar to retain the front of the end sections against separation.

In testimony whereof I affix my signature.
